POWER SUPPLY

George K. Turner, Palo Alto, Calif., assignor to Beckman Instruments, Inc., a corporation of California

Filed Dec. 1, 1958, Ser. No. 777,467

7 Claims. (Cl. 307—19)

This invention relates generally to a power supply and more particularly to a regulated power supply.

In many applications, it is desirable to have a source of relatively constant low voltage, high current power. For example, in colorimetry it is desirable to provide constant low voltage, high current power to a light source. In other applications, it is desirable to additionally provide a source of regulated high voltage. For example, in D.-C. amplifiers, the regulated low voltage, high current power may be employed as the heater supply to provide relatively constant current to the heaters of the associated tubes and the regulated high voltage may be employed as the plate voltage for the associated tubes.

It is a general object of the present invention to provide an improved low voltage, high current regulated power supply.

It is another object of the present invention to provide a power supply which supplies regulated low voltage, high current power and regulated high voltage.

It is another object of the present invention to provide a supply of the above character which employs in circuit a voltage regulator tube and at least one control transistor.

These and other objects of the invention will become more clearly apparent from the following description.

Referring to the drawing, the power supply includes a transformer 11 having a primary winding 12, and first and second secondary windings 13 and 14. The winding 13 is connected in a half wave rectifier circuit which includes the rectifier 15 and filter capacitor 16. The rectifier circuit provides a source of unregulated D.-C. voltage to the voltage regulating device, which may be a voltage regulating tube 17.

An output reference voltage of reduced voltage is obtained from a resistive bridge which includes a pair of arms comprising the resistors 19 and 21 and another pair of arms comprising resistor 22 and adjustable resistor 23. The two pairs of arms are joined by the resistor 18. By suitably choosing the resistors which form the bridge circuit, the high voltage is reduced to a level which corresponds to the desired regulated low output voltage at the terminals 29 and 30. By adjusting the relative values of the resistors in the bridge circuit, it is possible to compensate for voltage variations in the regulating tube due to line voltage variations and which variations are taken up by the resistor 18.

Regulated high voltage, determined by the voltage across the tube 17, is available at the terminals 27 and 28. The difference between the regulated voltage across the tube 17 and the unregulated voltage is taken up by the resistor 18. As previously described, this voltage may be used to supply plate voltage to the tubes associated with a D.-C. amplifier or the like.

A full wave rectifier circuit provides power to the output terminals 29 and 30. The rectifier circuit comprises rectifying devices 31 and 32 and filter capacitor 33. One terminal of the rectifier circuit is connected directly to the output terminal 29 and also to the line 24. The other terminal of the rectifier circuit is connected to the output line 30 through the collector to emitter path of a series regulating transistor 34. When a load is placed across the terminals 29 and 30 the circuit of the emitter of transistor 34 is completed to the line 24 whereby the transistor 34 acts as an emitter follower.

A second transistor 35 is connected in cascade with

2

the transistor 34. The emitter of the transistor 35 is connected to the base of the transistor 34 and the collector is connected in common with that of the transistor 34. The base voltage applied to the transistor 35 is derived from the voltage on the line 26.

5 The voltages available across the filter capacitors 16 and 33 are the line voltages times some constant which depends upon the turns ratio of the transformer and the drop in the rectifying devices. The voltage across the output terminals 29 and 30 is equal to the voltage between the lines 24 and 26 less a small constant voltage due to the base to emitter drop of the transistors 34 and 35 plus a small error due to line voltage variations.

10 The voltage on the line 24 is equal to the voltage at the line 28 times the ratio of the resistance of resistor 19 to the resistance of resistors 19 and 21. The voltage on the line 26 is equal to the voltage across the capacitor 16 (or the voltage at the line 28 minus the voltage across the resistor 18) times the ratio of resistance of resistor 23 to 15 the total resistance of resistors 22 and 23. The voltage between the line 26 and line 24 is equal to the difference of these voltages.

15 The voltage on the line 24 is equal to the voltage at the line 28 times the ratio of the resistance of resistor 19 to the resistance of resistors 19 and 21. The voltage on the line 26 is equal to the voltage across the capacitor 16 (or the voltage at the line 28 minus the voltage across the resistor 18) times the ratio of resistance of resistor 23 to 20 the total resistance of resistors 22 and 23. The voltage between the line 26 and line 24 is equal to the difference of these voltages.

25 A pair of cascaded transistors is employed whereby the current drawn by the low voltage regulating circuit is minimum since only a relatively small change of current is required on line 26 to cause a relatively large change in current flowing through the cascaded transistor 34. Variations in regulating voltage due to changes in current is minimized.

30 Apparatus in accordance with the foregoing was constructed. The various components shown in the figure were as follows:

Transistors:

34—2N 301A
35—2N 217

Tube: 17—OB2

Transformer:

Primary—110/220 volts
Secondary 14—30 volt C.T., 550 ma.
Secondary 13—110 volts, 15 ma.

Rectifiers:

15—Sarkes Tarzian 40K
31—Sarkes Tarzian 10K
32—Sarkes Tarzian 10K

Capacitors:

16—120 mfd., 250 volts
33—500 mfd., 25 volts

Resistors:

18—2.25K ohms
19—75K ohms
21—9.1K ohms
22—39K ohms
23—400 ohms

55 A voltage regulator in accordance with the foregoing served to provide an output current of 0.5 amp. at a voltage of 10.7. The variation in output voltage was less than 0.2% for line voltage variations between 100 and 130 volts. The output voltage varied less than 1% for 60 output current variations between 0.46 and 0.56 ampere.

65 Thus, it is seen that there is provided in combination a high voltage regulating device, for example, an inexpensive voltage regulating tube which acts as a reference for both the high voltage available at one pair of terminals, and for low voltage power available at another pair of terminals. A bridge circuit compensates for residual variations in output voltage of the low voltage circuit resulting from imperfect operation of the voltage regulator tubes, and the finite gain of the transistor regulators. A relatively inexpensive circuit which provides good high voltage and low voltage regulation is provided.

I claim:

1. A power supply comprising a first source of D.-C. voltage, a voltage regulating means connected to receive said D.-C. voltage and provide a regulated voltage, a second source of D.-C. voltage adapted to provide low voltage output power, a series regulating transistor having base, emitter and collector electrodes connected with the emitter and collector in series with the output from said second source, a bridge network connected to receive said regulated voltage and serving to provide a predetermined fraction of said regulated voltage across a circuit including the base of the series regulating transistor.

2. A power supply comprising a first source of unregulated D.-C. voltage, a voltage regulating means connected to receive said unregulated voltage and provide a regulated voltage, a second source of unregulated D.-C. voltage serving to provide low voltage output power, a series regulating transistor having base, emitter and collector electrodes connected with the emitter and collector in series with the output from said second source, a second transistor having base, emitter and collector electrodes connected in cascade with said first transistor and serving to control the base current in the same, a bridge network connected to receive the regulated voltage and serving to provide a portion of said voltage across a circuit including the base of said second transistor.

3. A power supply comprising a first source of unregulated D.-C. voltage, a voltage regulating means connected in circuit with said first source of unregulated D.-C. voltage and serving to provide a regulated voltage, a second source of unregulated D.-C. voltage, first and second output terminals connected to receive power from the second source, a series regulating transistor having base, emitter and collector electrodes connected with the emitter and collector electrodes in series with said first output terminal, a second transistor having base, emitter and collector electrodes connected in cascade with said first transistor and serving to control the base current flowing in the same, a first voltage divider connected to receive the regulated voltage and provide a portion of said voltage to the base of said second transistor, and a second voltage divider connected to the regulated voltage source and being connected to the second output terminal.

4. A power supply as in claim 3 wherein said voltage regulating means comprises a voltage regulating tube and additional output terminals serving to provide a regulated voltage output from said voltage regulating tube.

5. A power supply comprising a first source of unregulated D.-C. voltage, a voltage regulating means connected to receive said unregulated voltage and provide a regulated voltage, a second source of unregulated D.-C.

5 voltage serving to provide low voltage output power, a series regulating transistor having base, emitter and collector electrodes connected with the emitter and collector in series with the output from said second source, a second transistor having base, emitter and collector electrodes connected in cascade with said first transistor and serving to control the base current in the same, a resistive bridge circuit connected to receive the regulated voltage and serving to provide a voltage across a circuit including the base of said second transistor, said bridge circuit serving to correct for residual variations due to imperfect operation of the voltage regulating means and the finite gain of the transistor regulator.

6. A power supply comprising a first source of unregulated D.-C. voltage, means for regulating said first source of unregulated D.-C. voltage to provide a first source of regulated D.-C. voltage, serving to provide a low voltage output, variable impedance means connected to said low voltage output serving to regulate the same, a bridge circuit having a first pair and a second pair of terminals to receive the first regulated voltage and the first unregulated voltage respectively and serving to provide a reference input to said variable impedance at the output, said first and second pairs of terminals including one common terminal, said bridge circuit serving to correct for variations due to imperfect operation at said first source of regulated D.-C. voltage.

7. A power supply comprising a first source of unregulated D.-C. voltage, means for regulating said first source of unregulated D.-C. voltage to provide a first source of regulated D.-C. voltage, a source of D.-C. voltage adapted to provide low voltage output, variable impedance means connected to said low voltage output, and a bridge network means connected to receive said first unregulated voltage and said regulated voltage and serving to provide a predetermined fraction of the difference of said voltages as a reference to said variable impedance means.
